UNITED STATES PATENT OFFICE.

WILLIAM C. REINHARDT AND OSCAR H. BANKER, OF RACINE, WISCONSIN, ASSIGNORS
TO RACINE TOOL & MACHINE CO., OF RACINE, WISCONSIN.

PORTRABLE RAIL-HACKSAW.

1,336,443.

Specification of Letters Patent. Patented Apr. 13, 1920.

Application filed September 2, 1919. Serial No. 321,135.

To all whom it may concern:

Be it known that we, WILLIAM C. REINHARDT and OSCAR H. BANKER, citizens of the United States, and residents of Racine, 5 in the county of Racine and State of Wisconsin, have invented certain new and useful Improvements in Portable Rail-Hacksaws; and we do hereby declare that the following is a full, clear, and exact description 10 thereof.

This invention relates to power hacksaws, particularly those of the portable type which may readily be moved from place to place and easily set up.

15 It is an important object of this invention to provide a machine of this character which can be used for the sawing of railway rails, the various parts of the mechanism being so assembled that the machine may be secured in position and the work cut in a minimum space of time and much more quickly than it would be possible for the same work to be performed manually.

In cutting rails, particularly those used 25 in electric street railway work, it is usually necessary to remove a considerable portion of the ballast forming the road-bed and located on both sides of the rails. With the present type of machine, however, it is not 30 necessary to remove any greater quantity of this ballast than is required in manual sawing operations.

A further object is to provide the machine with adjustable bracing means for holding 35 the same against shifting and thus eliminate the possibility of breaking the saws during the reciprocation thereof.

With these and other objects and advantages in view, the invention consists in the 40 novel features of construction, combination and arrangement of parts which will be hereinafter more particularly described and claimed and shown in the drawings, in which:

45 Figure 1 represents a plan view of a portable hacksaw machine constructed in accordance with our invention and mounted upon portions of a pair of rails.

Fig. 2 is a transverse sectional view taken 50 on the plane of the line 2—2 of Fig. 1.

Fig. 3 is a side elevational view of the parts shown in Fig. 1, and

Fig. 4 is an enlarged elevational view of the supporting means used at one end of the machine and mounted upon a rail which 55 is shown in section.

The machine illustrated is primarily adapted for use in the repairing of electric car tracks, and is therefore driven by a suitable electric motor E. In other classes 60 of work, however, where it is not readily possible to procure electricity, other sources of power, such as an internal combustion engine, may be used, the machine being changed slightly to permit the attachment 65 of the other forms of driving means. Also other changes may be made in the machine, for instance in the form and proportion of the several parts and in the manner of securing the same upon the articles to be 70 operated on.

Referring more particularly to the accompanying drawings, the numeral 1 denotes a cross-tie having a pair of rails 2 secured thereto, said rails being spaced a considerable distance apart and ballasted on each side by concrete or crushed-stone material as shown at 3. The machine is disposed transversely of the rails and the saw 4 thereof is designed to cut through the head and 80 adjacent parts of one of the rails 2. As indicated in Fig. 3 portions of the ballast 3 are dug away on each side of the rail a sufficient distance to permit the saw to reciprocate. Although in the present embodiment of the invention the saw 4 is adapted only to cut through the ball or head of the rail, it is to be understood that it is within the contemplation of the invention to provide an arrangement whereby the rail may 85 be cut completely through.

The saw 4 is preferably of the drawcut type and the mechanism for reciprocating it and retaining it out of engagement with the work on its non-cutting stroke is 95 substantially similar to that shown in United States Patent No. 927,751, issued to Charles Rasmussen. This mechanism or any other which may be efficiently used is mounted upon a base plate 5, the same hav- 100

ing a pair of spaced supporting feet 6 which depend downwardly as shown in Figs. 3 and 4 and are provided with substantially U-shaped yokes 7 for straddling the heads 5 of the rails 2. Each of the yokes 7 has its outer arm provided with a threaded bearing sleeve 8 in which is disposed a clamping screw 9. From Fig. 4 it will be seen that the inner ends of the screws 9 engage beneath the rail-heads and are moved into or out of this position by the rotation of hand wheels or the like 10 formed on their outer ends.

The opposite end of the plate 5 terminates 15 slightly beyond the center of the road-bed and has a vertically adjustable support consisting of a ground-engaging foot 11 and an adjusting screw 12. As a result of this, after securing the feet 6 to one of the rails 20 2, the plate 5 may be leveled by raising or lowering the inner end thereof through the instrumentality of the screw 12.

Inasmuch as the saw 4 reciprocates longitudinally of the plate 5 and transversely of 25 the rails 2, there is a liability of considerable vibration and strain not only on the saw 4, but also on the plate 5. Therefore the latter is braced in the direction of its length by means of a brace bar 13, one end of which 30 has a rail-engaging shoe 14, while the other end is slideable in a socket 15 formed on the inner end portion of the plate 5. This socket 15 includes a pair of clamping ears whereby the extension-rod 13 may be secured in 35 adjusted positions to compensate for slight variations in the width of the track. The shoe 14 at the opposite end of the bar 13 consists merely of a depending shouldered member for engagement with the inner and 40 top portions of the head of the rail 2, this rail being remote from the rail which is being operated upon by the saw.

The hereinbefore mentioned electric motor is mounted upon the inner end portion 45 of the plate 5 and is connected with the main drive axle 16 of the saw reciprocating means by a worm and worm gear 17 and 18 respectively. The saw 4 is reciprocated longitudinally of the plate 5 adjacent the end thereof 50 to which the feet 6 are attached.

The operation of the invention is clearly discernible from the drawings and the preceding description, but it may be set out briefly as follows: After the ballast has 55 been dug away from the portion of the rail adjacent the point where the cut is to be made, the plate 5 carrying the saw reciprocating mechanism and the saw is placed on the rail to be cut and the ballast in such a manner that the saw 4 will be directly over 60 the point where the cut is to be made. After the yokes 7 have seated themselves on the head of the rail, the screws 9 may be tightened to engage beneath the rail-heads. After 65 the support 11 has been adjusted to sub-

stantially level the plate 5, the brace-bar 13 has one end inserted in the socket 15 and the other end engaged with the rail upon which it is not necessary at this time to operate. The socket 15 has the ears thereof 70 moved together to clamp the inner end of the rod 13 to said plate 5. The machine having been properly clamped and braced to the rails, the saw 4 may be lowered onto the work and the electric motor E or other 75 driving means started to procure the necessary action of the saw. Removal of the machine from its place of work may be even more readily accomplished than the placing thereof in position as there is no necessity 80 for the adjustment of parts. After the head of the rail has been sawed through, the rest may be cut by an ordinary hand-saw or in any other preferred manner.

We claim:

1. A portable machine of the class described including a base plate having operating mechanism mounted thereon, means at one end of the plate for securing the same adjacent the object to be operated upon, means for supporting the other end of the plate, and means for bracing the plate in one direction.

2. A portable machine of the class described adapted to span a pair of rails or the like and including a base plate having rail operating mechanism thereon, means at one end of the plate for securing the same adjacent the rail to be operated upon, the other end of the plate being spaced 95 from the other rail, and an extension brace member connecting said other end of the plate to the last mentioned rail.

3. A portable machine of the class described adapted to span a pair of rails or the like and including a base plate having rail operating mechanism thereon, means at one end of the plate for securing the same adjacent the rail to be operated upon, the other end of the plate being spaced from the other rail, adjustable supporting means for the last named end of the plate, and an extension brace member connecting said other end of the plate and the last mentioned rail.

4. A portable machine of the class described adapted to span a pair of rails or the like and including a base plate having rail operating mechanism thereon, a depending clamping foot at one end of said plate to adjustably secure the same to a rail, adjustable ground engaging supporting means at the opposite end of the plate, and an extension brace member connecting the last mentioned end of the plate and the adjacent rail.

5. A portable machine of the class described adapted to span a pair of rails or the like and including a base plate having saw-operating mechanism thereon, a saw re-

ciprocable longitudinally of the base plate by said mechanism, means for securing one end of the base plate to the rail to be operated upon by said saw, supporting means 5 for the other end of the plate, and a longitudinally extending brace bar connecting the last mentioned end of the plate and the adjacent rail, whereby to brace the plate

longitudinally and secure the same between the pair of rails.

In testimony that we claim the foregoing we have hereunto set our hands at Racine, in the county of Racine, and State of Wisconsin.

WM. C. REINHARDT.
O. H. BANKER.
